UNITED STATES PATENT OFFICE

WILLIAM W. STEWART, OF BROOKLYN, NEW YORK.

BAND-FASTENING.

SPECIFICATION forming part of Letters Patent No. 293,812, dated February 19, 1884.

Application filed December 11, 1883. (No model.)

To all whom it may concern:

Be it known that I, WILLIAM W. STEWART, a citizen of the United States, residing in Brooklyn, in the county of Kings and State of New York, have invented certain Improvements in Band-Fastenings, of which the following is a specification.

This fastening is designed particularly for bracelets which consist of a flat band of metal; but it is applicable also to other metal bands—such as bale-ties—and, indeed, to any flat band one end of which it is desired to fasten adjustably to the other end or to another like band.

Figure 1 of the accompanying drawings is a perspective view of a bracelet constructed according to my invention. Fig. 2 is a plan thereof devoid of ornamentation. Fig. 3 is a section of the clamp detached. Fig. 4 is an edge view thereof. Fig. 5 is a side view of Fig. 2, and Fig. 6 is a longitudinal section cut along the line 6 6 in Fig. 2. The remaining views illustrate modifications, and will be described hereinafter.

Referring to Fig. 1, let A designate a sheet-metal band designed to pass around the wrist, and B a clamp or fastening device connected to one end, *a*, thereof, and adapted to receive the other end, *b*, and clamp the two together. This clamp B is better shown in Figs. 2 to 6. It consists of a plate pivoted at *c* to the end *a* of the band, and having a slot or passage, *d*, formed through it flatwise, through which the ends *a b* of the band may pass, the passage having lateral extensions *e e* of contracted thickness, as shown in Figs. 3 and 4. The thick passage or slot *d* is of greater thickness than the superposed ends *a b* of the band, so that when one is lying in it the other may readily be passed through. The lateral extensions *e e* are made considerably thinner than the slot *d*, and taper as they recede therefrom, joining the slot at its thickness, and tapering to a thickness slightly less than that of the two ends *a b* of the band at their edges, as shown in Fig. 4. These extensions *e e* are shown in Fig. 3. The end *a* of the band is inserted into the slot *d*, and the two are connected by the rivet *c* on the back. The clamp B may then be turned on the band as far as the extensions *e e* will admit. The clamp being turned, as shown in Figs. 2 and 3, with the end *a* in the wide slot *d*, the other end, *b*, may be inserted to any required

distance, in order to adapt the bracelet to any size of wrist, and then by turning or twisting the clamp B the extensions *e e* will be caused to engage the two layers of the band and pinch them together. The farther it is turned the tighter it will wedge itself against these ends, and the latter against each other. In practice it will simply be twisted by the fingers until conveniently tight, when the pressure will be sufficient to keep the ends from pulling apart under any strain to which a bracelet is ordinarily subject. The bands may be straight and plain, as in Fig. 8, in which case friction alone is relied upon to fasten them; or they may be corrugated, as shown in Figs. 1, 5, and 6, in which case their corrugations coincide and fit together, and when the clamp is twisted they are kept from separating far enough to disengage the corrugations, and so are fastened together in a positive manner. The passage or slot *d* must be made thick enough to admit the two bands when their corrugations are opposed or alternate, instead of coinciding, in order to permit the end *b* to be inserted past the end *a*.

Fig. 7 is a front view of a modification, whereof Fig. 8 is a side view. Fig. 9 is a section of the clamp. Fig. 10 is an edge view thereof; and Fig. 11 is a view similar to Fig. 7, showing the fastening applied. This form differs from that already described only in that the pivot *c* is placed outside the edge line of the band *a*, and there is consequently only one slot-extension *e*. The clamp is turned as shown in Fig. 7. The end *b* is then thrust through the slot *d*, and the clamp is turned back to the position shown in Fig. 11, or until the fastening is made tight.

Fig. 12 shows another fastening similar to the one just described, but with the clamp B made from two plates riveted together at *c* and *f*. Fig. 13 is an edge view thereof. Fig. 14 shows the position of the clamp before slipping through the end *b*, after which the clamp is turned down, as in Fig. 12.

Figs. 15 and 16 show another modification, being views similar, respectively, to Figs. 12 and 14. There are two clamps, B B, pivoted to opposite edges of the band *a*, and working from opposite sides. After the end *b* is slipped through, they are pressed together, as shown in Fig. 15.

Figs. 17 and 18 are views answering to Figs. 2 and 6, and showing a modified method of constructing the clamp B. The latter is made of a shell of metal, presenting an external appearance of solidity, the ornamentation of its surface being effected by striking it up in dies, thereby forming ornamental depressions or indentations. The depth and arrangement of these are so determined that when the clamp is turned the deepest ones shall embrace and clamp between them the two layers *a b* of the band. This construction is consequently practically identical with that first described, the difference being that the former has contracted 15 slots *c c*, joining the wide slot *d* by straight lines, and with substantially plane interior surfaces, whereas in the latter the lines are irregular and follow the design, and the interior surfaces are of varying height and uneven contour. The clamping in both cases is the same.

Fig. 19 is a view answering to Fig. 2, and showing a modification wherein a circular clamp is used, pivoted to the band beyond the edge line thereof, and capable of being turned 25 on this pivot (*c*) to either side. It is shown in full lines in the open position, and in dotted lines in the clamped position. When the latter position is reached, a spring catch or tongue, *g*, enters a notch in the clamp and holds the 30 latter from turning back.

My invention is applicable to bale-ties, strap-fastenings, and other uses, as well as to bracelets.

I claim as new—

35 1. A fastening for bands or straps, consisting of a movable clamp embracing the same, and provided with a slot or passage through

it of sufficient width to admit two superposed layers or thicknesses of the band or strap, and with a lateral extension of said slot or passage, 40 the thickness of which is less than that of the superposed layers of the band or strap, whereby, when the clamp is turned until the layers of the band or strap are forced into this lateral extension, they are pressed tightly together 45 and so fastened, substantially as set forth.

2. The combination, with the end *a* of a band, of a clamp, B, pivoted thereto, and provided with a passage or slot, *d*, therethrough, and with a lateral contracted extension, *e*, of 50 said passage, constructed and adapted to operate substantially as set forth.

3. The combination of band A, the ends *a b* of which are corrugated with interlocking corrugations, with a clamp, B, connected to 55 said band, and having a slot or passage, *d*, of sufficient thickness to admit the ends *a b* and permit them to be slid past each other therein, and a lateral extension, *e*, of said passage contracted to less thickness than the superposed ends *a b* when their corrugations are interlocked, adapted to operate substantially as set forth.

4. The combination of band A, clamp B, formed with passage *d* and contracted lateral 60 extension *e*, and pivot *c*, joining the clamp to the band, substantially as set forth.

In witness whereof I have hereunto signed my name in the presence of two subscribing witnesses.

WILLIAM W. STEWART.
